UNITED STATES PATENT OFFICE

2,625,720

PUMP FOR TYPE CASTING

John R. Ross, Chicago, Ill., assignor to International Newspaper Supply Corporation, Chicago, Ill., a corporation of Illinois

Application December 16, 1949, Serial No. 133,405

4 Claims. (Cl. 22—79)

1

My invention relates to an improved pump for use in transferring molten type metal from a pot to a type casting mold.

In type casting for newspaper and other printing, it is necessary to transfer molten type metal from a containing pot to the type casting mold. Successful casting demands that the transferred metal be of predetermined temperature and that the amount transferred be adequate for the mold. Safety of personnel and economy dictates that the flow of metal be readily shut off to avoid possible overflow and burns.

In accordance with the present invention, an improved pump for transferring molten type metal is achieved wherein a control arm located above the pot of molten metal controls the transfer. Flow discontinues promptly after the control arm is released, thereby providing a "dead man" safety feature to prevent accidental spillage of the metal. In addition, the apparatus of the present invention includes a rotatable delivery nozzle that may be adjusted at will to deliver metal back to the pot or to deliver the metal to a plurality of points over the sides of the pot. This feature permits the user to shift the nozzle to deliver metal to one type case while another is being placed in an adjacent position for filling. When the first cast is filled, the nozzle is simply swung to the new position over the second cast to deliver metal thereto.

Further in accordance with the present invention, the pump is provided with an impeller located in an impeller chamber having an outlet passage closed off by a gate valve. The gate valve defines a metal escape port when in the closed position, thus permitting escape of any metal trapped in the delivery nozzle when the valve is closed. In the open position the gate valve closes the escape passage.

It is therefore a general object of the present invention to provide an improved pump suitable for delivering molten type metal from a pot to a type cast.

Another object of the present invention is to provide an improved pump to deliver molten metal from a pot to a type cast and having safety means to discontinue metal flow when released.

A further object of the present invention is to provide an improved pump to deliver molten metal from a pot to a type cast and having a valve automatically operable to release entrapped metal when flow is discontinued.

Yet another object of the present invention is to provide an improved pump to deliver molten type metal from a pot to a type cast and having

2

a removable delivery nozzle that is swingable to any one of many positions to deliver the metal.

The novel features which I believe to be characteristic of my invention are set forth with particularity in the appended claims. My invention itself, however, both as to its organization and mode of operation, may best be understood by reference to the following description taken in conjunction with the accompanying drawings, in which:

Figure 1 is a cross-sectional view of a metal pot showing the pump of the present invention in elevation;

Figure 2 is a view like Figure 1 showing the pump in the tilted position;

Figure 3 is a cross-sectional view of the pump taken along axis 3—3, Figure 1, showing parts in elevation;

Figure 4 is a cross-sectional view through the axis 4—4, Figure 3, showing the valve in the open position; and

Figure 5 is a view like Figure 4, showing the valve in the closed position.

Referring now to Figure 1, there is shown at 10 a pot for molten type metal having an upper marginal lip 10a. The pot contains type metal 12 and is heated by suitable means (not shown) to maintain the metal in a molten condition. This metal is to be delivered over the sides of the pot 10 to type casts in measured amounts to cast the desired printing plates.

The pump of the present invention includes a frame 14 having a pad 14a that seats on the lip 10a of the pot 10. The pad 14a defines a hook-shaped member 14b that threadedly carries the set screw 15. The latter is screwed tight to clamp the frame snugly in place.

The frame 14 has a forked portion 14c extending over the pot 10 on each side of the pump indicated generally at 20. The sides of the forked portion terminate in aligned holes 14d, Figure 3, that receive the cylindrical portion of the headed and threaded pin-bolts 18, thus securing the pump 16 in position for rocking movements about the axis defined by bolts 18 which is, of course, parallel to the surface of the molten metal 10a.

The pump is locked in any desired position of tilt by the arms 18a and 18b. These arms are pivotally secured to the opposite sides of the carriage 20 by pin defining bolts 22 which are threadedly received in the carriage 20 and have cylindrical pin defining portions that are received in the arms 18a and 18b to form pivotal supports therefor. The arms 18a and 18b each

have an elongated slot 18c, Figure 1. The slot on the arm 18a receives the adjustable lock bolt 24 which is threadedly received in the frame 14 and has a handle 24a by which it may be rotated to lock the arm 18a at any desired position relative to the frame 14. The elongated opening 18c of the arm 18b receives the pin bolt 24b, Figure 3, which merely defines an arm guiding pin and does not lock the carriage in position.

The carriage 16 has an upwardly extending bracket portion 16a which receives the motor 26. The motor is attached to the bracket portion 16a by suitable bolts 27.

Immediately below and in line with the motor 26, the carriage 16 has body portion 16b, shown in cross-section in Figure 3. A pair of spaced bores 16c are provided in the lower end of this portion of the carriage. A pair of depending support rods 28 are snugly received in these openings and are secured therein by the pins 28a, which extend through the rods and the adjacent portions of the carriage 16.

At their lower ends the rods 28 carry the housing 30, this housing being secured to the rods by the nuts 28b which are received by the threaded end portions 28c of the rods 28. The rods 28 are formed with reduced diameter at their lower portions 28d to be received in the openings provided in the housing 30 and to form annular seats against which the housing 30 abuts, thus holding the housing in fixed position relative to the carriage 16.

The housing 30 defines an impeller chamber 30a at its lower end. This chamber is in communication at its bottom with the liquid in the pot 10 and at its side is in communication with the outlet passage 30b. As seen best in Figure 5, the outlet passage 30b is located in the portion 30c of the housing 30 which extends sidewardly of the impeller chamber. This portion of the housing is curved as shown to conform to the shape of the passage 30b.

An impeller 32 is located in the impeller chamber 30a. This impeller is mounted on the shaft 34 which is received in a suitable bore 30d in the housing 30 and extends up through the body portion of the carriage 16 to the coupling 36. At coupling 36, the shaft 34 is connected to the shaft 26a of the motor 26.

The shaft 34 is held in place relative to the carriage 16 by the ball bearing 38, Figure 3, and the sleeve bearing 40.

As seen best in Figures 3 and 5, the impeller 32 defines a pair of complementary helical surfaces 32a. When the shaft 34 is rotated by the motor 26, these surfaces lift the molten metal in the pot 10 to urge the metal from the bottom of chamber 30a to the top thereof, thereby forcing the metal into the channel 30b.

Control of the metal flow through passage 30b is effected by the gate valve indicated generally at 40. The housing 30 is cut out in a rectangular gate valve passage or raceway 30e, Figure 5, extending from the upper face of the housing to the lower face thereof and passing through the channel or passage 30b as seen in Figures 3 and 5. The gate valve 40 is of mating rectangular cross-section and slides in this passage to open and close the passage 30b.

The gate valve 40 is provided with a circular opening 40a which mates with the channel 30b when the valve is in the lifted or open position shown in Figure 4. When the valve is in the lowered or closed position of Figure 5, the opening 40a is below the passage 30b and the flow of

fluid through the passage 30b obstructed. It then becomes an agitator.

The operating mechanism for the gate valve 40 is seen best in Figure 1. As shown, the valve is pinned at its upper end to the lift rod or link 42 which extends upwardly in parallel relation with the rods 28. At its upper end the link 42 is pinned to the crank arm 44 which is attached to the shaft 46 carried by the carriage 16. The operating handle or arm 48 is likewise affixed to the shaft 46 and extends forwardly to a point near the delivery pipe 50. The volume of flow is adjustably determined by the stop 47 which bears against the adjustable bolt 45.

In accordance with the present invention, the valve 40 is dropped to the closed position of Figure 5 when the arm 48 is released. This is accomplished by making the length and weight of arm 48, together with the length and weight of the crank 44, and the weight of the rod 42 and the valve 40 sufficient to overcome any buoyancy of the valve 40 and link 42 in the heavier molten type metal and to overcome the frictional opposition to downward movement of the valve 40 when the arm 48 is released. Consequently, the valve automatically assumes the closed position when released and the possibility of accidental pumping of the molten type metal is reduced.

Downward movement of the valve 40 and link 42 is arrested by the stop bolt 52 which is threadedly received in the valve 40 at a point where its head rests on the housing 30 when the valve is in the desired closed position shown in Figure 5.

In addition to the rectangular slide valve passage or raceway 30e, the housing 30 has an escape port 30f, Figure 5. This port extends along the valve passage from the fluid passage 30b to the bottom of the housing 30 as shown. It is enlarged at 30g to form a seat for the toe portion 40b of the valve 40, with which it mates when the valve is in the open position shown in Figure 4.

As is described in further detail hereafter, the escape port 30f prevents freezing of metal in the outlet pipe and at the same time permits normal pumping operations when the valve is open.

As seen best in Figure 4, the housing 30 is threaded at 30b where the passage 30b turns upwardly and reaches the upper face of the housing. This threaded portion of the housing receives a complementary threaded pipe 54 which extends upwardly a short distance and receives the pipe coupling 56 to define an enclosed seat.

The upper portion of the threads on the pipe coupling 56 is obliterated to form a cylindrical bore. This bore receives the bottom end 50a, Figure 4, of the outlet pipe 50, Figure 1. This pipe extends upwardly to a point above the seat of the pot 10 and then turns approximately 90 degrees to the substantially horizontal portion 50b, as shown in Figure 1. The portion 50b terminates in the downwardly sloping nozzle 50c from which the molten metal flows.

The delivery pipe 50 is held in position by the bracket 58 which extends forwardly from the carriage 16. The bracket is formed with a semi-circular seat for the pipe 50 and receives a mating U-shaped member 58a which is held in place by the screws 58b. The parts 58 and 58a thereby define a ring to hold the pipe 50 in upright position. However, the pipe fits loosely in this ring so that it may be rotated at will to direct the molten metal in any desired direction. A lug 57, Figure 2, is welded to the pipe 50 and bears

against the bracket 58 to prevent rise of the pipe out of the socket.

The ability of the present structure to direct the molten metal in any desired direction is particularly desirable when type molds are cast in rapid succession. While one type mold is being cast, the next mold may be placed in an adjacent position so that it is merely necessary to rotate the pipe 50 to deliver metal in the new direction required for casting of the next type mold. This process can be continued indefinitely to obtain practically continuous use of the pump and associated metal pot.

When the flow of metal through the pipe 50 is interrupted by valve 40, it is possible to trap metal in the portions of the pipe above the level of the metal in the pot 10. Since this portion of the pipe is exposed to the cool atmosphere, the metal can freeze and thus render the unit inoperative. This is prevented by the escape port 30b which defines an uninterrupted path for fluid flow when the valve 42 is in the closed or lowered position shown in Figure 5. In this position the shoe 40b is spaced from the housing 30.

The port 30f does not influence operation of the pump when the valve 40 is in the open position of Figure 4, since the shoe 40b then seats in the portion 30g of the port 30f to obstruct fluid flow therethrough.

When the valve 40 is in the lowered or closed position of Figure 5, the outlet passage from chamber 30 is obstructed. The impeller then causes circulation of the molten metal in the pot 10, thereby mixing the metal and maintaining a uniform temperature in it.

In the view of Figure 2 the pump of the present invention is shown in a tilted position with the rods 28 at a substantial angle relative to the vertical. The pump is held in this position by the lock 24 and operates in the same manner as is described above. The ability of the pump to operate and be adjusted to the tilted position shown permits operation of the pump in shallow tanks and, in addition, provides a method of lowering the height of the nozzle 50c without substituting a new delivery pipe 50.

It will be observed that the carriage 16 has an axis defined by the opening provided for the shaft 34 and that the carriage is rockable about an axis transverse to this axis and defined by the pin-bolts 18. The latter axis is parallel to the surface of the fluid in the pot 10.

If for any reason metal does freeze in the pipe 50, it may be removed by loosening the bolts 58b and immersed in the pot 10 or otherwise heated to melt the metal and free the pipe.

While I have shown and described a specific embodiment of my invention, it will of course be understood that I intend by the appended claims to cover all variations and alternative constructions falling within the true spirit and scope of my invention.

What I claim as new and desire to secure by Letters Patent of the United States is:

1. A pump adapted for transferring molten type metal from a pot to a type cast, comprising an elongated frame having means connected thereto for suspending said frame with the bottom portion thereof submerged within said pot, a hollow housing providing therein an impeller chamber secured to the lower portion of said frame, said chamber having an outlet opening and an open bottom providing an inlet opening communicating directly with the interior of said pot when said pump is suspended therein, a

pipe terminating in a nozzle connected to said outlet opening and adapted to extend upwardly over the side of said pot, a gate valve means located adjacent said pipe to slide across said outlet opening and thereby control the flow of metal therethrough, said gate valve means including a slidably mounted gate member moving from open to closed position through a generally vertical plane, said gate member being linked to an elevating handle mounted on the upper portion of said frame and arranged thereon so that said gate member when raised in open position will be lowered and closed automatically by gravitational force when said handle is released, a motor mounted on the upper portion of said frame, a rotatably suspended shaft driven by said motor and the lower end thereof extending into said impeller chamber, and an impeller mounted on the end of said shaft immediately above said inlet opening for rotation within said housing but in close spacial proximity to said inlet opening, whereby said impeller is effective in pumping the type metal through said pipe when said gate valve means is open while serving as a mixing agitator to maintain uniformity in said type metal within the pot when said gate valve means is in its normally closed position.

2. A pump and control valve therefor adapted for transferring molten type metal from a pot to a type cast, an elongated frame having means connected thereto for suspending said frame with the bottom portion thereof submerged within said pot, a hollow housing having an inlet and outlet opening secured to the bottom of said frame, said housing providing therein an impeller chamber and a passage extending laterally from said chamber to said outlet opening, a gate member slidably mounted in a generally vertical position across said passage adapted to allow metal to flow through said passage when said gate member is raised and to stop the flow therethrough when lowered, said gate member being linked to an elevating handle mounted on the upper portion of said frame so that said gate member when raised will be closed automatically by gravitational force when said handle is released, a pipe terminating in a nozzle connected to said outlet opening and extending upwardly over the side of said pot, a motor mounted on the upper portion of said frame equipped with a shaft extending downwardly into said impeller chamber, and an impeller mounted on the end of said shaft to direct the type metal through said housing.

3. A pump and control valve therefor adapted for transferring molten type metal from a pot to a type cast, comprising an elongated frame having means connected thereto for suspending said frame with the bottom portion thereof submerged within said pot, a hollow housing having an inlet and outlet opening secured to the bottom of said frame, said housing providing therein an impeller chamber and a passage extending laterally from said chamber to said outlet opening, a gate member slidably mounted in a generally vertical position across said passage adapted to allow metal to flow through said passage when said gate member is raised and to stop the flow therethrough when lowered, said gate member being linked to an operating handle mounted on the upper portion of said frame, a pipe terminating in a nozzle connected to said outlet opening and extending upwardly over the side of said pot, a motor mounted on the upper portion of said frame equipped with a shaft extending downwardly into said impeller chamber, and an

impeller mounted on the end of said shaft to direct the type metal through said housing, said gate member being slidably mounted within slots in the top and bottom of said housing and also being provided with an opening through the lower portion thereof alignable with said passage when said gate member is raised, the lower of said slots being considerably larger than said gate member to provide a drainage port for the material in said pipe when said gate member is closed to stop the flow therethrough, and said gate member having an enlarged lower end seatable within said enlarged lower slot to close said drainage port when said gate member is raised to open position.

4. In a pump and control valve structure adapted for transferring molten type metal from a pot to a type cast, the combination comprising a frame having means connected thereto for suspending said frame with the bottom portion thereof submerged within said pot, a hollow housing having an inlet and outlet opening secured to the bottom of said frame, said housing providing therein an impeller chamber and a passage extending laterally from said chamber to 25 said outlet opening, said housing also being equipped with vertically aligned slots above and below said laterally-extending passage, a gate member slidably mounted in said slots and extending across said passage, said gate member being arranged to allow the metal to flow through said passage when said gate member is raised and to stop the flow therethrough when lowered, a pipe connected to said outlet opening and extending upwardly over the side of said pot, and 35 impeller means, located in said impeller chamber, for drawing molten type metal into said impeller

5 chamber and forcing said type metal into said laterally extending passage and upwardly through said pipe, the lower of said slots being considerably larger than said gate member to provide a drainage port for the material in said pipe when said gate member is closed to stop the flow therethrough, said gate member having an enlarged lower end seatable within said enlarged lower slot to close said drainage port when said gate member is raised to open position.
